UNITED STATES PATENT OFFICE.

LOUIS WILLIAM CHOBAR, OF LANCASTER, NEBRASKA.

REED CLIPPER.

Application filed August 15, 1927. Serial No. 213,058.

The object of my said invention is the provision of an efficient device through the medium of which reeds such as used in clarinets, saxophones, and other analogous musical instruments may be expeditiously clipped in a clean cut manner.

To the attainment of the foregoing, the invention consists in the improvement as hereinafter described and definitely claimed.

10 In the accompanying drawings, forming part of this specification:—

Figure 1 is a top plan view of the preferred embodiment of my invention with a reed positioned to be clipped.

15 Figure 2 is an enlarged end elevation of the same.

Figure 3 is a fragmentary longitudinal central section, with parts in elevation and with the reed omitted.

20 Figure 4 is a fragmentary view showing inverted a portion of the bottom of the body of my novel device.

Similar numerals of reference designate corresponding parts in all the views of the drawings.

25 The reed to be clipped is designated by 1 and is shown in Figures 1 and 2.

Among other elements my novel device comprises a body, preferably of appropriate metal, and having a bottom wall 2 and side walls 3. The inner sides of the side walls 3 are undercut adjacent to the upper side of the bottom wall 2 as indicated by 4 for the endwise slidable insertion in the body of a strip 5, designed to support the reed to be clipped. The said strip is preferably of close grained wood with a smooth planed surface. The strip 5 is designed to afford a smooth surface for clean cutting of reeds, and while the said strip is preferably formed of wood I would have it understood that within the purview of my invention the strip 5 may be of any other material compatible with the purpose ascribed to the strip 5. I would also have it understood that the strip 5 may be adjusted lengthwise in the body so as to insure a smooth surface, and that the strip 5 may be reversed or turned end for end, and when the said strip is deteriorated by long continued use it may be expeditiously and easily removed and as readily replaced with a new strip or block 5.

30 In the bottom wall 2 of the body is formed an opening 6, Figures 3 and 4, and in com-

munication with the ends of said opening 6 are guide ways 7 which are continued upwardly in the inner sides of the side walls 3 as designated by 7* in Figure 3.

35 Fixed with respect to the body and preferably formed integral therewith is an arch 8 in which is a central aperture 9 and a countersink 10.

40 At 11 is the blade holder of my improvement, the said blade holder being provided with end portions 12 movable rectilinearly in the said guide ways 7, 7*. The said blade holder is of general arcuate form in plan, and is provided in its under side with a socket 13 to receive the heel portion of a 45 clipping blade 14, the said blade 14 being preferably, though not necessarily, secured to the said socket through the medium of pins 15.

45 Appropriately fixed to the holder 11 is 50 a stem 16. The said stem 16 is guided in the before mentioned aperture 9 in the arch 8 and is provided by preference with a detachably connected head or knob 17. A coiled spring 18 is seated in the before mentioned 55 countersink 10 of the arch 8 and is arranged about the stem 16 and is interposed between the bottom wall of the said counter sink 10 and the head 17 so as to operate to retract the blade holder 11 subsequently to a depression thereof.

60 By virtue of the provision of the opening 6 in the bottom wall 2 of the body it will be manifest that it is feasible to form the stem 16 integral with or to permanently 65 affix the said stem 16 to the body 11, the body 11 and the stem 16 being introduced upwardly through the opening 6 and the stem 16 being moved upwardly through the aperture 9, after which the spring 18 is 70 applied and the head or knob 17 is connected to the upper end of the stem 16. In the practical use of my novel device, the reed 1 to be clipped is positioned in the device as shown in Figures 1 and 2, after which 75 the blade 14 is powerfully depressed by pressure applied to the head or knob 17, whereupon the reed will be clipped in a clean cut manner so that the clipped reed will be quite as good as an entirely new 80

85 reed.

Manifestly my novel device may be made in different sizes for clarinets and saxophone reeds.

90 It will also be apparent from the fore-

110

going that my novel reed clipping device is simple and inexpensive in construction, and is devoid of delicate parts such as are likely to get out of order after a short period of use.

Incident to the use of my novel device it will be appreciated that the reed may be expeditiously and easily positioned for the clipping operation, and after said operation the reed may as readily be removed from the device.

I have entered into a detailed description of the preferred embodiment of my invention in order to impart a full, clear, and exact understanding of the said embodiment. I do not desire, however, to be understood as limiting myself to the construction disclosed, my invention being defined by my appended claims within the scope of which modifications may be made without departure from my invention.

Having thus described the invention, what I claim as new is:—

1. A device for clipping musical instrument reeds, comprising a body having a bottom wall and side walls with undercuts in their inner sides adjacent to the bottom wall and also having an arch on the side walls and an aperture and a counter sink in said arch, and further having guide ways in the side walls, a supporting block disposed on the bottom wall and in the said under cuts of the side walls, a blade holder movable in said guide ways, an arcuate

blade carried by said holder, a stem fixed to said holder and extending through said aperture in the arch and provided at its upper end with a head, and a spring surrounding the stem and seated in said countersink and interposed between the bottom of the countersink and the head. 35 40

2. A device for clipping musical instrument reeds, comprising a body having a bottom wall and side walls with undercuts in their inner sides adjacent to the bottom wall and also having an arch on said side walls and an aperture and a counter sink in said arch, and further having guide ways 45 in the side walls, a supporting block disposed on the bottom wall and in the said under cuts of the side walls, a blade holder movable in said guide ways, an arcuate blade carried by said holder, a stem fixed to said holder and extending through said aperture in the arch and provided at its upper end with a head, and a spring surrounding the stem and seated in said countersink and interposed between the bottom of the countersink and the head; the 50 said bottom wall of the body being provided with an opening below the blade holder and blade, and the said guide ways in the side walls of the body being extended through the bottom wall of the body and arranged in communication with the said opening. 55 60 65

In testimony whereof I affix my signature.

LOUIS WILLIAM CHOBAR.
